(57) **CLAIM**

The ornamental design for a bottle, as shown and described.

DESCRIPTION

FIG. 1 is a top perspective view of a bottle in accordance with a first embodiment.

FIG. 2 is a bottom perspective view of the bottle shown in FIG. 1.

FIG. 3 is a left side view of the bottle shown in FIG. 1.

FIG. 4 is a right side view of the bottle shown in FIG. 1.

FIG. 5 is a front side view of the bottle shown in FIG. 1.

FIG. 6 is a rear side view of the bottle shown in FIG. 1.

FIG. 7 is a top view of the bottle shown in FIG. 1.

FIG. 8 is a bottom view of the bottle shown in FIG. 1.

FIG. 9 is a top perspective view of a bottle in accordance with a second embodiment.

FIG. 10 is a bottom perspective view of the bottle shown in FIG. 9.

FIG. 11 is a left side view of the bottle shown in FIG. 9.

FIG. 12 is a right side view of the bottle shown in FIG. 9.

FIG. 13 is a front side view of the bottle shown in FIG. 9.

FIG. 14 is a rear side view of the bottle shown in FIG. 9.

FIG. 15 is a top view of the bottle shown in FIG. 9; and,

FIG. 16 is a bottom view of the bottle shown in FIG. 9.

The uneven broken lines represent boundaries of the design and form no part of the claimed design. The even broken lines represent portions of the article that form no part of the claimed design.

1 Claim, 10 Drawing Sheets

Related U.S. Application Data

a division of application No. 29/750,853, filed on Sep. 16, 2020, now Pat. No. Des. 932,300.
